UNITED STATES PATENT OFFICE.

YORKE BURGESS, OF CHICAGO, ILLINOIS, ASSIGNOR, BY MESNE ASSIGNMENTS, TO INTERNATIONAL AUTOMATIC SIGNAL COMPANY, OF KANSAS CITY, MISSOURI, A CORPORATION OF MISSOURI.

RAILWAY BLOCK-SIGNALING SYSTEM.

1,026,200.

Specification of Letters Patent. Patented May 14, 1912.

Application filed October 18, 1910. Serial No. 587,748.

To all whom it may concern:

Be it known that I, YORKE BURGESS, a citizen of the United States, residing at Chicago, in the county of Cook and State 5 of Illinois, have invented certain new and useful Improvements in Railway Block-Signaling Systems, of which the following is a specification.

My invention relates to improvements in 10 railway block signaling systems, and in many of its features particularly to systems wherein the signals are displayed upon the moving train through the agency of electrical devices generally located in the locomotive cab.

One of the objects of my invention is to provide a closed circuit system,—that is, one in which the common track and the track contacts or "controls" normally coöperate 20 with electrical connections on the cab to provide a closed main circuit, and in which, also, the track relays are in normally closed track circuits,—so that rupture of the essential circuit connections may cause signaling 25 operations.

Another object of my invention is to provide a system in which the track contact devices or "controls" for coöperation with the cab circuit connections may be made 30 physically a part of the track-rails proper, so as to dispense with a third rail or other extraneous devices, and to minimize the expense of installation.

Another object of my invention is to provide 35 a system in which the cab signals may indicate the direction from which any signal received comes, and wherein provision is made for automatically stopping the train in the event that the signal system indicates danger ahead of the train, but without stopping the train should danger in rear thereof be indicated.

Many other and further objects will become apparent to those skilled in the art 45 from the following description taken in conjunction with the accompanying drawings, in which I have diagrammatically illustrated an embodiment of the invention.

In the drawings, Figure 1 indicates diagrammatically the track wiring of five blocks or sections; Fig. 2 indicates diagrammatically the devices and circuits appurtenant to the cab apparatus; and Fig. 3 indicates diagrammatically the association

of a cab system of a train with the track 55 system, indicating the operation of the cab signals under a certain condition.

In the drawings, 10 and 11 indicate the rails of a "blocked" track. Rail 10 is divided into blocks, as by insulating bodies, 60 12, and this rail I will term the "block" rail. The rail is electrically continuous throughout each block (except for insulated signaling points or "controls" to be described). The rail 11 is electrically continuous 65 through successive blocks in the preferred embodiment shown (except for insulated signaling points or "controls" in each block), and this rail 11 I will distinctively refer to as the "continuous" rail. 70

Each block of the track is equipped with a local battery 13 bridged between the continuous and block rails, 11 and 10, at one end of the block, and with a track relay 14, bridged by wires 15 and 16 between said 75 rails 11 and 10, at the opposite extremity of the block. Thus each track relay is normally in a closed local circuit, to be shunted by the short circuiting of the track should a train pass into the block between the battery and the relay.

Each track relay 14 may be of any appropriate construction preferably to provide two armatures, 17 and 17' respectively, to govern the electrical connection of certain "controls" or signaling points in foreign blocks in opposite directions from the local or home block of the relay, so that the signaling range of each relay extends both in advance of and in rear of home block, 80 local to the relay. For the purpose of definition, I will hereafter arbitrarily term the direction to the right of any relay on the drawings, as in front of the relay, and the direction to the left as in rear of the relay. 85

Each armature, 17 and 17', governs the condition of certain "danger controls" or contact points in the first foreign block, in the appropriate direction, and also certain "caution controls" or contact points in the 100 second foreign block in the same direction. In general these controls or contact points are electrical contact members insulated from the common rails but adapted to be electrically connected with the rails through the 105 operation of the appropriate governing relay. Specifically, I prefer that said controls or contact points should be embodied di-

rectly in the trackage, in the form of rail sections insulated from the common track, and in the drawings, 10^c and 10^d, indicate respectively caution and danger controls or 5 insulated sections in the rail 10, and 11^c and 11^d indicate similar controls in rail 11. The common track is made electrically continuous by bonding the rail ends to span such insulated sections, as shown at 6.

10 To consider specifically the wiring of one relay 14, both of its armatures, 17 and 17', are connected by wires 18 and 18' to the wire 15, which is connected to the continuous rail 11. Armature 17, which governs 15 the forward blocks, has a front contact point 19, connected by wire 20 to the distributing wire 21, electrically connected with all of the danger controls 10^d in the block rail 10 of the foreign block next in advance thereof, 20 so that as long as the relay armature 17 is attracted, all of said danger controls 10^d in the next forward block have electrical connection through the parts 21, 20, 19, 17, 18, 15, with the common track of the trackage 25 system. This connection is of sufficiently low resistance to constitute substantially a direct connection between the control and the common track. A second front contact 30 23 for armature 17 has connection by wire 24 with the caution control or controls 10^c in the block rail of the second foreign block ahead of the relay normally to connect the caution control to the common track. A back contact 25 is provided for armature 17, 35 having connection to resistance coil 26, the opposite terminal of which is connected to the caution control wire 24, so that it will plainly appear that as long as the armature 17 is attracted, the caution control 10^c of the 40 second foreign block in advance of the relay has low resistance connections with the common track rail 11, by the path 10^c, 24, 23, 17, 18, 15, 11, but when the armature 17 drops back against back contact 25, the electrical connection of said caution control to 45 rail 11 is effected through the resistance by path 10^c, 24, 26, 25, 17, 18, 15, 11. The rear armature 17' of the relay has connections identical in kind and arrangement with those 50 of the armature 17 (corresponding parts being indicated by like numerals of reference differentiated by the exponent prime [']), but the wiring connections of the rear armature 17' extend to the danger controls 11^d 55 and caution control 11^c in the continuous rail 11 of the trackage in rear of the home block. Thus, when any given relay is de-energized, as by the presence of a train within its home block, its respective front 60 and rear armatures, 17 and 17', affect the electrical condition of the danger and caution controls appurtenant to the block rail 10 in advance of such relay, and appurtenant to the continuous rail 11 in 65 rear of such relay, for advantageous pur-

poses which will hereafter become apparent. Thus, it will be seen that in general the trackage equipment provides a track relay for each block, bridged across the common track to receive current supply from a local bridged battery, such relay providing two armatures, respectively connected to work in opposite directions from the relay to govern the condition of controls in foreign blocks, each armature when attracted 70 acting electrically to connect both the danger and caution control points governed thereby with the common track and, when retracted, acting to open the wiring connections of the danger controls, thereby to isolate them from the common track, and, further, to interpose resistance in the connection of the caution control with the common track. In general I prefer, as herein shown, to distribute 75 danger control points at intervals throughout each entire block, but it is generally sufficient to provide for each block a caution control only near the forward end of the block with reference to the direction of train movement, so that a caution signal will not 80 be given until the train is about to leave the block, and enter into a danger zone. 85 The cab signal apparatus provides, in general, a source of current supply, and main circuit connections therefor, terminating in 90 wheel contacts arranged to be closed through the rails when the train is running on common track and to be affected by the condition of the connections between any "control" or signaling point and the common track. 95 With such main circuit are associated electro-responsive signal devices, operating in response to the condition of the main circuit, 100 and so governed by the condition of the controls, said signal devices being arranged by their resultant operation to govern the signals and the train-braking or stopping appliances. In the specific construction shown 105 110 duplicate sets of signal apparatus are provided on the engine cab, one to be governed wholly from the right wheels and the other wholly from the left wheels of the engine. Specifically, 30 indicates an insulated contact wheel of a locomotive running on block rail 10 and 30' a corresponding insulated wheel, running on continuous rail 11. 31 and 31' indicate two electrically connected wheels running on the respective rails 10 and 11, connection being effected as through 115 an axle, 32, and said connected wheels being arranged at some little distance from the insulated wheels. For example, the connected wheels may be part of the tender or carriage equipment, and the individually insulated wheels part of the engine equipment. Since the parts of the two circuit systems are 120 substantially duplicate, I will describe only 125 one thereof, the other set of instruments 130

being designated by similar numerals differentiated by the exponent prime ('). Thus, wheel 30 is connected by wire 33 with one terminal of a suitable current generator 34, 5 while the axle 32 for wheel 31 has connection by wire 35 common to the two sets of apparatus, with a branch wire 36, including a "danger" relay D and terminating in a front contact 37, for the armature 38 constituting part of the main circuit, which continues from the tail of the armature by wire 39 to the opposite terminal of the generator 34. A "caution" relay C is arranged in the main circuit in multiple with relay D, connection 40 being made from the wire 35 through the relay coil to a front contact 41 with which normally contacts the armature 42 which is connected to the wire 39. It will be apparent that since both relays C 20 and D are of the "stick" type, the circuit once established (through the path 34, 33, 30, 10, 31, 32, 35, and parallel branches 40, C, 41, 42, 39; and 36, D, 37, 38, 39, back to the generator 34) will continuously energize both relays C and D and self-maintain said circuit closed as long as proper electrical connection is effected between the wheels 30 and 31. But, should the main circuit be so affected between wheels 30, 31, 25 as to cause either relay to release its armature, the armature will remain retracted until it is manually restored to attracted position. The relays C and D are respectively so wound that "caution" relay C is 30 much weaker than the "danger" relay D, so that the interposition between wheels 30 and 31 of a resistance (such as is furnished by a track-relay coil resistance 26) will effectively deenergize caution magnet C, but will not deenergize "danger" magnet D.

The signaling devices proper are preferably lamps, arranged to be energized from the generator 34, and disposed in circuits such that when both armatures 38 and 42 45 are in normal attracted position, a white light is displayed, and when armature 42 alone is retracted, a green light is displayed, and when both armatures are retracted, a red light is displayed, the circuits for these 50 lights being wholly local to the train, and having no inclusive connection with the contact wheels. Specifically, the white light, W, has one terminal connected by wire 43, to the front contact 41, for caution relay C, 55 and its remaining terminal connected by wires 46 and 47, with the appropriate terminal of the generator 34, so that under normal conditions the white light is energized through the circuit 34, 39, 42, 41, 45, W 46, 47, 34. The green light, G, has one terminal connected by wire 48 with the rear contact, 49, of armature 42 for the caution 60 relay C, its opposite terminal being connected by wire 50 through a spring switch 65 51,—arranged to be opened by armature 38

of the danger relay D,—with the wire 47, so that when the caution relay alone is deenergized the green light is lighted through the circuit 34, 39, 42, 49, 48, G, 50 (including switch 51), 47, 34. The red light, R, has 70 its terminals respectively connected by wire 52 to the back contact 53 of armature 38 for the danger relay D, and by wire 54, to the common wire 47, so that when the danger relay is deenergized, it breaks the green light circuit at the switch 51, and closes the red light circuit 34, 39, 38, 53, 52, R, 54, 47, 34. Now, 75 remembering that the operation of a track relay in any block caused by the presence of a train in the local block affects the control points on the rail 10 in front of the local block and of the rail 11 in rear of the local block, it will be apparent that a train approaching said occupied block from either direction will have its left hand wheels, 80 30'—31', coöperate with such affected controls or signal points, such left hand wheels, as shown in Fig. 2, being those which govern the condition of the signaling devices on the right hand side of the cab under the supervision of the engineer, the duplicate set of signaling devices being on the left hand side of the cab under the supervision of the fireman. Thus, except when an engine is backing, danger or caution ahead will always be 85 indicated on the engineer's set, and danger or caution behind on the fireman's set, so providing for distinction between the signals received to indicate the direction from 90 which the signal comes.

With the signaling apparatus described, I preferably provide a brake-controlling magnet, B, arranged in any suitable fashion to cause the setting of the train-brakes when the magnet is deenergized and its armature 105 permitted to drop; mechanisms so to set the brakes are well known and need not here be described. Such magnet I preferably arrange in a circuit controlled by the armature of the danger relay which indicates danger-ahead, so that the brake will be set whenever danger ahead is indicated, and I further preferably provide automatic means for switching the brake magnet circuit into association with the engineer's signaling set, when the engine is moving forwardly, and into association with the fireman's signaling set when the engine is backing, thereby to insure that the brakes will be set when, and only when, danger in the 110 direction of engine movement is indicated by the signal system. In this way, I insure that when one train approaches another from the rear, the brakes on the approaching train will be set as soon as the danger indication is given, while the brakes on the leading train will not be set, thereby leaving it free to proceed forwardly to clear the track for the following train or otherwise 115 to avoid the danger of rear-end collision. 120 125 130

In the specific construction shown the brake magnet B has one terminal connected by wire 56 with a switch lever 60, arranged to move between two contact points, 61 and 61', the former connected by wire 62 to the wire 33, and the other correspondingly connected by wire 62' to the wire 33' of the opposite signaling set. The remaining terminal of the magnet has duplicate connections, one extending by wire 63 through a spring switch 64 to a front contact 65 for the danger-relay armature 38 of the fireman's set, and the other similarly wired with respect to the engineer's set. The switch 60 is preferably arranged for automatic operation in harmony with the movement of the engine reversing lever, R. L., so that when the lever is thrown as indicated in Fig. 2 to drive the engine forwardly, switch 60 makes contact with point 61', and close the spring switch 64', opening the opposite corresponding contacts. Thus, under the conditions indicated in Fig. 2, a circuit for the brake magnet B is established by the path 34', 39', 38', 65', 63', 64', B, 56, 60, 61', 62', 34'. Obviously, therefore, should relay D' become deenergized, showing danger ahead, brake magnet B will also become deenergized, causing the brakes to set; but an indication of danger behind, resulting in the deenergization of relay D of the fireman's set, will not affect the brake magnet as the circuit connections for associating said brake magnet with the fireman's set stand open at contact 61 and switch 64. Obviously, however, when the engine is backed, the throwing of the reverse lever R. L. automatically shifts the brake magnet connections into operative association with the fireman's set, and throws the brake magnet under the control of the danger relay D, cutting out the control of the engineer's danger relay D'.

In Fig. 3 I have shown conditions existing in the cab circuit of a train X as it approaches, along block 1, a train Y, in block 3. It will be observed that the presence of train Y in block 3 has caused the deenergization of relay 14 appurtenant to said block, causing its armature 17' to retract, opening the circuit connections at contact 19' and 23', and closing the circuit connections at 25'. Thus, for the caution control or contact, 11^a, in the left hand rail of block 1, (assuming the direction of movement of train X to be that indicated by the arrow) a resistance connection is established through the common track rail 11 by the path 24', 26', 25', 17', 18', 15, 11, while each of the danger controls 11^a in block 2, is isolated from the track, its possible connection circuit (21', 20', 19', 17', 18', 15, and 11) being open between contact point 19' and track relay armature 17'. Accordingly when train X

reaches the position indicated in full lines in the drawing, (where its insulated wheel 30 coacts with the caution control 11^a of block 1, while its connected wheels 31-31', rest upon common track rails 11 and 10,) the interposition of the resistance 26' in the main circuit (from generator 34' by the path 33', 30', 11^a, 24', 26', 25', 17', 18', 15, 11, 31, 32, 35, parallel branches 36', and 40', through relays D' and C', their armatures 38' and 42', and the common return wire 39' back to the generator) so decreases the current flow that the weaker caution relay C is effectively deenergized, thereby to drop its armature 42, cutting said relay out of circuit and closing a circuit for the green light G' (through the path 34', 39', 42', 49', 48', G', 50', 51', 47', back to the generator 34'). This caution signal, being displayed on the engineer's side of the cab indicates the presence of a train, or some equivalent condition, in the second block in advance. Assuming, now, that the train X is run slowly forward until it reaches the first danger control, 11^a, in block 2, as indicated in dotted lines in Fig. 3, as soon as the insulated wheel 30' comes in contact with said control point 11^a (which is wholly isolated from the common track by the breaking of the connection 17-19' at the track relay 14 for block 3), the main circuit is completely broken between the wheels 30'-31', and the danger relay D' thereby becomes deenergized, dropping its armature 38', closing the circuit for the red light R' (34', 39', 38', 53', 52', R', 54', 47', 34') and also breaking the connection for the brake magnet B, at 65'. Therefore, not only is the red light R' displayed on the engineer's side of the cab, indicating danger ahead, but the brake magnet, by its release, is caused in any appropriate way to set the brakes as the result of the dropping of its armature. Should the train A be placed in jeopardy by any condition existing in rear of it, the same signaling operations are capable of performance on the signaling set on the fireman's side of the train, except that the occurrence of a danger condition, causing the dropping of the armature 38 of danger magnet D with a consequent glowing of the red light R will have no effect whatever upon the brake magnet B, owing to the disassociation of said brake magnet from the signaling set on the fireman's side of the cab under the conditions assumed.

As graphically illustrated in Fig. 3, a broken rail, interrupting the circuit relay 14 for block 3, will have the same effect as the presence of a train within the block and provision may readily be made so that the presence of a car on a side track within fouling distance of the main track may have the same effect, appropriate zones of the side track being bonded, as at s' and s'', to

the main track so that the presence of a car thereon in the switch will short circuit the appropriate relay 14 as effectively as though the car were on the main track.

5 While I have herein described in some detail a particular embodiment of my invention which I believe to be new in many of its details of organization and arrangement, it will be apparent to those skilled in the art that many changes in the specific embodiment of the invention might be made without departure from its spirit and within the scope of the appended claims.

What I claim is:

15 1. In a block signaling system, the combination of a track providing a continuous rail and a rail divided into block sections; a track circuit for each block including a track relay, two sets of control contacts for each block, respectively for connection with track relays in advance and in rear thereof, each set comprising a danger contact and a caution contact, two sets of connections controlled by each track relay extending respectively in advance of the local block of the relay and in rear of said local block, each such set of connections normally connecting directly a danger contact with the continuous rail and a caution contact with the continuous rail; and a cab signaling system comprising two main circuits having separate contact members respectively arranged to coöperate with the two sets of control contacts of any block, and caution signal and danger signal display means for each said main circuit.

2. In a block signaling circuit, the combination of a track divided into blocks, a track circuit for each block including a track relay, two sets of insulated control contacts for each block, two sets of connections controlled by each relay extending respectively in advance of the local block and in rear of the local block of said relay, the forwardly extending connections controlling the electrical association of certain control contacts of one set with the track and the rearwardly extending connections controlling the electrical association of certain control contacts of the other set with the track; and a cab signaling system comprising two main circuits having separate contact members respectively arranged to coöperate with the two sets of control contacts, each such main circuit including a source of current supply carried by the cab, and a motor part for brake-control arranged for operative association with either main circuit alternatively.

60 3. In a block signaling system, the combination of a track divided into blocks; two sets of insulated control contacts for each block, a track circuit for each block including a track relay, connections controlled by each said relay governing the electrical asso-

ciation with the track of certain controls of one set in advance of the local block, and of certain controls of the other set in rear of the local block; and a cab signaling system comprising two main circuits respectively dependent upon the connection of the two sets of control contacts, each such main circuit including a source of current supply, electro-responsive devices, display means associated with each said electro-responsive device; a motor part for brake control; and means for connecting said motor part to be governed by one of the electro-responsive devices of either main circuit.

4. In a block signaling system, the combination of a track divided into blocks, two sets of insulated control contacts for each block, a track circuit for each block including a relay; connections controlled by each said relay governing the electrical association with the track of certain control contacts of one set in advance of the local block and certain control contacts of the other set in rear of the local block, and a cab signaling system comprising two main circuits respectively dependent upon the condition of the two sets of control contacts along the track, each such main circuit comprising a source of current supply and an electro-responsive device, a brake-controlling magnet, means connecting said brake-controlling magnet to be governed by the electro-responsive device of either main circuit; and means for association with the engine reversing lever for connecting said brake-controlling magnet to be governed alternatively by one or the other of said two electro-responsive devices, according to the position of said reversing lever.

5. In a block signaling system, the combination of a track divided into blocks; a track circuit for each block including a track relay, insulated control contacts disposed in foreign blocks in advance of and in rear of the local block of each relay, electrical connections for each relay governing the association of said control contacts respectively in advance and in rear of the local block with the track; and a cab signaling system comprising two main circuits arranged respectively for inclusion of said advance control contacts and said rear control contacts, signal display means responsive to the condition of said respective main circuits, and brake-controlling means arranged for association alternatively with either of said main circuits to be governed by the condition thereof.

6. In a block signaling system, the combination with a track divided into blocks, of a source of current supply and a track relay for each block, control contacts in foreign blocks in opposite directions from each said relay, respectively associated with opposite sides of the track, circuit connections for,
